UNITED STATES PATENT OFFICE.

HARRY B. SMITH, OF BROOKLYN, NEW YORK, ASSIGNOR TO STOKES & SMITH COMPANY, OF PHILADELPHIA, PENNSYLVANIA, A CORPORATION OF PENNSYLVANIA.

MACHINE FOR GLUING BLANKS.

1,179,672.

Specification of Letters Patent. Patented Apr. 18, 1916.

Application filed February 11, 1915. Serial No. 7,570.

To all whom it may concern:

Be it known that I, HARRY B. SMITH, a citizen of the United States, residing at Brooklyn, in the county of Kings and State of New York, have invented new and useful Improvements in Machines for Gluing Blanks, of which the following is a specification.

This invention relates to machines for applying glue to blanks, and is an improvement upon the invention set forth in Patent No. 726,473, issued to me on April 28, 1903, for a machine for gluing blanks.

The machine set forth in the specification of the patent referred to embodied two oppositely disposed rollers, or rolls, comprising separated circular collars, the faces of which performed the function of applying glue to the blank which was fed past the rolls. The arrangement was such that the glue applying faces of one roll were out of alinement with the glue applying faces of the opposite roll. When the blank moved past the rolls the first roll to be engaged by it applied the glue to the blank in a plurality of stripes, each stripe corresponding to one of the glue applying faces upon that roll. As the blank passed the other roll a second series of stripes of glue was applied to the blank, the said stripes being intermediate of the other stripes and being wide enough to completely fill the uncoated space between the stripes formed by the first roll. Hence the blank left the machine with a continuous broad band or zone of glue applied to it. Where the blank was to be used as a covering for paper boxes usually this zone of glue extended completely across the blank so that the entire face of the blank was covered with glue.

The machine referred to also embodied a roll which carried glue to the glue applying faces, said roll being arranged so that the glue applying faces of the rolls rolled upon it. The degree of pressure of the faces of the glue applying rolls to the roll which carried the glue to them could be regulated by an adjusting device. Although this machine operates very satisfactorily when properly adjusted, it has been found, in practice, that the operator of the machine should take care that the adjustment of the two rolls is the same, that is, the two glue applying rolls should bear with substantially the same pressure upon the roll which

supports them and which may carry to them the glue or substance which they are to apply to the blank. And if the pressure of the two glue applying rolls is not the same, one of the rolls will take up and deliver more glue than the other, and a non-uniformity in the gluing of the blanks takes place; and evidently if the pressure of one of the rolls is insufficient, that roll will not carry a sufficient quantity of the glue to the blank.

A principal object of the present invention is to produce a machine to perform the same general functions as the machine referred to above, but which will operate effectively to insure a uniform application of the glue to the blanks, and without necessitating special care of the operator to attain this end.

In such machines the glue or other substance to be applied to the blank is usually carried in a receptacle or tank and a glue feeding roll or "wallower" is provided which dips into the bath of glue in the tank and as it rotates, feeds the glue toward the glue applying rolls. One of the objects of the present invention is to provide an improved arrangement for mounting this glue feeding roll which greatly facilitates its disengagement from the other mechanism with which it connects and which rotates it.

A further object of the invention is to construct the machine in such a way as will greatly facilitate the accessibility of the moving parts, and particularly of the rolls.

In the present embodiment of the invention the collars of the glue applying rolls rest directly on a supporting roll which transfers the glue to them from the glue-feeding roll. This transfer roll is preferably covered with a yielding covering such as rubber. The pressure of the collars tends to wear furrows in this covering. One of the objects of this invention is to overcome this tendency so far as possible and to equalize and distribute the effects of use on this transfer or supporting roll.

Further objects of the invention will appear more clearly hereinafter.

The invention consists in the general combination of parts and features to be set forth hereinafter, all of which contribute to produce an efficient gluing machine.

A preferred embodiment of my invention will be particularly described in the follow-

ing specification, while the broad scope of my invention will be pointed out in the appended claims.

In the drawings, Figure 1 is a vertical section through a gluing machine embodying my invention. Fig. 2 is a plan of the machine shown in Fig. 1, certain parts being broken away. Fig. 3 is an elevation and partial section showing one end of the machine. Fig. 4 is an end elevation and partial section.

Referring more particularly to the parts, the machine frame preferably comprises two end frames or housings 10 and 11, which 5 may, if desired, be supported on the flanges of the receptacle or tank 12, in which the bath of glue is placed. Referring more particularly to Fig. 1, these end frames preferably comprise a base frame 13 and an upper 10 frame 14, said frames preferably being clamped together and forming a bearing 15 between them for the end of the shaft 16 of a roll 17. The axis of this roll 17 is preferably disposed midway between two substantially 15 vertical guideways 18 which are formed in the upper frame 14. These guideways 18 are for the purpose of holding in position glue applying rolls 19 and 20, and they hold the rolls so that they are free to 20 move upwardly in the guides. The shafts 21 of these rolls preferably fit neatly in the guideways 18. The roll 19 is provided with a plurality of spaced collars 22 which are disposed a slight distance apart substantially 25 throughout the entire length of the roll. These collars are of circular form and present glue applying faces 22 which roll upon the surface of the supporting roll 17. The means for supporting the glue applying 30 rolls is entirely devoid of any adjustment whatever, and the pressure exerted by each glue applying roll upon the supporting roll is simply its own weight, or any weight which it may support.

Above the glue applying rolls I prefer to 35 provide presser rolls 23, which are in the form of simple cylindrical rolls, the shafts 24 of which are preferably received in the guideways 18. The surfaces of these presser 40 rolls are not in contact with the surface of the glue applying rolls, but are preferably held a slight distance away from them. In order to accomplish this I prefer to provide the rolls 19 and 20 with supporting rollers 45 25 (see Fig. 3) disposed near each end of the machine, and on these rollers 25 similar rollers 26 rest, said rollers 26 being carried on the shafts of the presser rolls. It is understood also that the presser rolls rest with 50 their weight upon the glue applying rolls, and there is no adjusting means for changing the degree of this pressure. From this arrangement it is evident that the pressure or weight exerted by the two rolls 19 and 20 on the roll 17 is the same, and it cannot be

altered so as to interfere with the perfect operation of the machine as might occur in the case of a machine having a defective adjustment.

The pressure of the glue applying rolls 19 and 20 being the same, the amount of glue which they pick up from the supporting roll 17 is the same, and hence when the blank is fed through the machine over the upper faces of the glue applying rolls the amount of glue applied to the blank by the two rolls 75 will be substantially uniform.

The blanks which are to be fed through the rolls are preferably supported on one side of the machine in any suitable manner, such as on a drop table 10^a. In the operation of the machine a small pack of blanks are fed from the table 10^a through the machine, and in passing through, these blanks engage the under faces of the presser rolls 85 23 and tend to lift them slightly. In this way the weight of the presser roll is utilized to press the blank against the glue applying faces of the rolls 19 and 20.

In order to strip the blank from the first 90 glue applying roll 19 and guide it to the second roll 20 any suitable guiding means may be provided. The means illustrated comprises the longitudinally disposed guide bar 27 which extends longitudinally of the 95 machine between the two glue applying rolls. This guide bar has a plurality of guide fingers or plates 27^a which project into the space between the glue applying faces 22 of the roll 19, and the rear ends or tails 100 28 of these fingers project toward and in line with the glue applying faces 22 of the roll 20. As a further means for guiding the blank between the rolls I provide another set of guide fingers 29, which project toward 105 the rear of the machine and which project over the shaft 21 of the roll 20, and the upper edges of the said guide fingers 29 are depressed below the upper sides of the glue applying faces 22 of the roll 20. The rear 110 extremities 30 of these fingers, however, project beyond the glue applying faces so that as the blank proceeds toward the rear of the machine they will engage the blank and take it from the roll, delivering it with the glued side uppermost upon an inclined delivery table 31. This delivery table is preferably supported pivotally at 32 so as to enable it to be swung out of the way for a purpose which will appear more fully hereinafter. In order to support the guide bar 27 I prefer to form inverted U-shaped sockets 33 at its ends, and these sockets are adaptable to be received over small blocks 34 attached on the inner sides of the frame members 14 (see Fig. 2).

I prefer to utilize the roll 17 not only as means to support the glue applying rolls, but also prefer to utilize it as a transfer roll for transferring the glue to the rolls. In

order to feed the glue from the glue holding receptacle to the roll 17 I prefer to provide a feed roll or wallower 38 which runs in the bath of glue and I preferably mount this roll in such a way that it can be readily driven from the driving mechanism; and furthermore so that it can be readily disengaged and swung up or withdrawn out of contact with the glue. For this purpose I prefer to provide two supporting arms 35 which provide bearings 36 for the ends of the shaft 37 of the feed roll 38. The under surface of this roll, when it is in the position indicated in Fig. 1, dips in the bath of glue in the receptacle 12, and when in this position a driven gear wheel 39, which is rigid on the shaft of the roll 38, meshes with a driving gear wheel or pinion 40 which is rigid with the roll 17. The arms 35 are supported on-pivotal supports or pins 41, which pins are loosely mounted in brackets 42 which may be supported on the upper edges of the receptacle or tank 12. These brackets have outwardly disposed extensions or aprons 43 which form a gap 44 between them, and in this gap each arm 35 is mounted on the pin 41.

The arms 35 are preferably connected to the pins 41 in such a way that they can be adjusted away from the roll 17 in order to disengage the gear 39 from its driving gear 40 before swinging the arms up. For this purpose I prefer to provide each arm 35 with a substantially horizontal extension 44, and each of these extensions are formed with a longitudinal guide slot 45, through which the pin 41 passes. Extending into the outer end of the extension 43 I provide an adjusting screw 46 which passes through 40 and has a threaded connection with the pin 41, the inner end of the said screw abutting against the inner end of the slot 45, as at the point 47. The outer end of the screw 46 has a shank 48 which is preferably of 45 angular form, and this shank is provided with a hand wheel 49, by means of which the screw can be rotated. Between the outer end of the slot 45 and the pin 41 I prefer to provide a coiled spring 50 which is disposed 50 around the screw and which forces the arms outwardly when the screw 46 is rotated in the proper direction to adjust the roll 38 back into its working position. When the roll 38 is in its working position the axis 55 of the pivot 41 is approximately in line with the axes of the shafts 16 and 37. Also when the roll 38 is in its working position the weight of the rolls is preferably supported on the edges of the tank 12, for which purpose I prefer to provide the arms 35 with laterally projecting lugs 51.

When the roll 38 has been adjusted away from the roll 17 and the arms 35 swung upwardly, these arms may be supported in the 60 position indicated by the dotted line 35^a

(see Fig. 1), for which purpose I prefer to provide each bracket 42 with an inclined face 52 which will be engaged by a seat 53 formed on the back or outer edge of the arm. When the roll is supported in this position 70 the axis 37^a of the roll will be disposed slightly to the left of the pins 41 so that the roll tends by gravity to remain in this position.

I prefer to form the feed roll 38 of considerably smaller diameter than the gear wheel 39 which drives it, and the surface of this roll is in contact with the surface of the roll 17. From this arrangement the peripheral speed of the roll 17 is higher than 75 that of the roll 38, and this arrangement has a desirable effect because it enhances the transfer of the glue to the roll 17, for evidently it produces a wiping effect of the surface of the roll 17 on the roll 38.

I prefer to drive the glue applying rolls 19 and 20 positively, and this is preferably accomplished through the medium of a large driving gear 55 rigid on the shaft 16, said gear meshing with gear wheels or pinions 56 which are attached to the shafts of the rolls 19 and 20. I prefer also to drive the presser rolls positively, and for this purpose I prefer to provide the ends of their shafts with gear wheels 57 which mesh with the gears 56. In this connection attention is called to a certain function of the rollers 25 and 26 consisting in this: that these rollers prevent the teeth of the gears 56 and 57 from meshing too closely together. Of course when blanks are passing between the glue applying rolls and the presser rolls they lift the presser rolls slightly, which causes a slight separation of the meshing teeth of the gear wheels 56 and 57, but this does not prevent the transmission of rotary movement between the two.

In order to prevent the pressure at the glue applying faces 22 from wearing grooves in the rubber cover 17^a on the roll 17 I prefer to provide means for shifting the points of contact by shifting the rolls longitudinally with respect to each other. For this purpose I prefer to mount the shaft 16 so that it can slide longitudinally in its bearings, and beyond the pinion 40 (Figs. 3 and 4), I provide a disk 58, the edge of which runs in a cam groove 59 in a cam 60 on the shaft 37. As the cam rotates it therefore shifts the shaft and roll 17 longitudinally to and fro gradually. This distributes the wear and furthermore tends to distribute the glue uniformly on the transfer roll. The upper part of the housings 10 forms 110 horizontal rests 10^b which can be used to temporarily support the rolls when removing or replacing them in the machine as indicated at 10^c.

The inclined receiving shelf 31 may be 115 swung up to the position indicated at 31^a 120

when the roll 38 is swung up to the position 38^a. The machine may be driven continuously from a suitable source of power which rotates the pinion 55^a.

5 It is understood that the embodiment of the invention described herein is only one of the many embodiments or forms the invention may take, and I do not wish to be limited in the practice of the invention nor in 10 my claims to the particular embodiment set forth.

On account of the fact that the rolls 19 and 20 have freely movable or "floating" shafts, if it should happen that a cloth or 15 other obstruction comes between them and the roll 17, the rolls will not be injured or warped in any way. Such cloths are used in cleaning and may become accidentally caught in the rolls as suggested. It is also 20 evident that if such a cloth passed upwardly between the rolls 17 and 38 the shaft 37 of the roll 38 could swing upwardly and outwardly on the arms 35 so that no injury would be done to the rolls in this event.

25 What I claim is:—

1. In a gluing machine for applying glue to a blank, in combination, a receptacle for the glue, a pair of glue applying rolls mounted opposite to each other and each 30 having spaced glue applying faces for applying glue from said receptacle to the blank, a supporting roll under said glue applying rolls and supporting said glue applying rolls by pressure thereupon at said 35 glue applying faces, the said faces of one of said glue applying rolls being out of alignment with the said faces of the other of said glue applying rolls, whereby said glue applying rolls will apply stripes of glue to the 40 blank moving in one direction past said rolls, the totality of said stripes forming a continuous zone of glue on the blank, the weight exerted through said glue applying rolls to said supporting roll being the sole 45 means of applying pressure therebetween.

2. In a gluing machine for applying glue to a blank, in combination, a receptacle for the glue, a pair of glue applying rolls mounted opposite to each other and each 50 having spaced glue applying faces for applying glue from said receptacle to the blank, a supporting roll under said glue applying rolls and supporting said glue applying rolls by pressure thereupon at said 55 glue applying faces, the said faces of one of said glue applying rolls being out of alignment with the said faces of the other of said glue applying rolls, whereby said glue applying rolls will apply stripes of glue to the 60 blank moving in one direction past said rolls, the totality of said stripes forming a continuous zone of glue on the blank, means for guiding the blank past said glue applying rolls, means for guiding said glue applying rolls so that they are freely movable

upwardly from said supporting roll, the weight exerted through said glue applying rolls to said supporting roll being the sole means of applying pressure therebetween.

3. In a gluing machine for applying glue 70 to a blank, in combination, a receptacle for the glue, a pair of glue applying rolls mounted opposite to each other and each having spaced glue applying faces for applying glue from said receptacle to the 75 blank, a supporting roll under said glue applying rolls and supporting said glue applying rolls by pressure thereupon at said 80 glue applying faces, the said faces of one of said glue applying rolls being out of alignment with the said faces of the other of said glue applying rolls, whereby said glue applying rolls will apply stripes of glue to the blank moving in one direction past said 85 rolls, the totality of said stripes forming a continuous zone of glue on the blank, and presser rolls disposed over and exerting their weight upon said glue applying rolls, the weight exerted through said glue applying rolls to said supporting roll being 90 the sole means of applying pressure therebetween.

4. In a gluing machine for applying glue to a blank, in combination, a receptacle for the glue, a pair of glue applying rolls mounted opposite to each other and each having spaced glue applying faces for applying glue from said receptacle to the blank, a supporting roll under said glue applying rolls and supporting said glue applying rolls by pressure thereupon at said 95 glue applying faces, the said faces of one of said glue applying rolls being out of alignment with the said faces of the other of said glue applying rolls, whereby said glue applying rolls will apply stripes of glue to the blank moving in one direction past said rolls, the totality of said stripes forming a continuous zone of glue on the blank, and presser rolls disposed over said glue applying rolls, said presser rolls having supporting collars, said glue applying rolls having supporting collars under and supporting said presser-rolls at said collars and holding said presser rolls with the under faces thereof out of contact with the glue applying faces, the weight exerted through said glue applying rolls to said supporting roll being the sole means of applying pressure therebetween.

5. In a gluing machine for applying glue to a blank, in combination, a frame having a pair of oppositely disposed substantially vertical guides, a pair of glue applying rolls having shafts lying in said guides, said rolls having spaced glue applying faces for applying glue to the blank, a supporting roll under said glue applying rolls and supporting said glue applying rolls by pressure thereupon at said glue applying faces, the 125 130 135

said faces of one of said glue applying rolls being out of alignment with the said faces of the other of said glue applying rolls, whereby said glue applying rolls will apply 5 stripes of glue to the blank moving in one direction past said rolls, the totality of said stripes forming a continuous zone of glue on the blank, the weight exerted through said glue applying rolls to said supporting roll being the sole means of applying pressure 10 therebetween.

plying glue to the blank, a supporting roll under said glue applying rolls and supporting said glue applying rolls by pressure thereupon at said glue applying faces, the said faces of one of said glue applying rolls 70 being out of alinement with the said faces of the other of said glue applying rolls, whereby said glue applying rolls will apply stripes of glue to the blank moving in one direction past said rolls, the totality of said 75 stripes forming a continuous zone of glue on the blank, the pressure exerted by each of said glue applying rolls upon said supporting roll being substantially equal for both rolls, the weight upon said glue applying 80 rolls being the sole means for exerting pressure of the glue applying rolls on said supporting rolls.

15 therebetween.

6. In a gluing machine for applying glue to a blank, in combination, a frame having a pair of oppositely disposed substantially vertical guides, a pair of glue applying rolls having shafts lying in said guides, said rolls having spaced glue applying faces for applying glue to the blank, a supporting roll under said glue applying rolls and supporting said glue applying rolls by pressure thereupon at said glue applying faces, the said faces of one of said glue applying rolls being out of alignment with the said faces of the other of said glue applying rolls,

20 whereby said glue applying rolls will apply stripes of glue to the blank moving in one direction past said rolls, the totality of said stripes forming a continuous zone of glue on the blank, the weight exerted through

25 said glue applying rolls to said supporting roll being the sole means of applying pressure therebetween, and a pair of presser rolls having shafts also lying in said guides, said presser rolls being supported on said

30 glue applying rolls.

35

9. In a gluing machine for applying glue to blanks, in combination, a receptacle for the glue, glue applying rolls, a feed roll adapted to dip in the bath of glue in the receptacle, a gear wheel rigid with said feed roll for rotating the same, a driving gear wheel rotating about a fixed axis and adapted to drive said first named gear wheel when meshing therewith, and means supporting said feed roll and adapted to swing said feed roll out of contact with the glue and away from said driving gear to disengage said driven gear therefrom. 95

35 glue applying rolls.

7. In a gluing machine for applying glue to a blank, in combination, a frame having a pair of oppositely disposed substantially vertical guides, a pair of glue applying rolls 40 having shafts lying in said guides, said rolls having spaced glue applying faces for applying glue to the blank, a supporting roll under said glue applying rolls and supporting said glue applying rolls by pressure 45 thereupon at said glue applying faces, the said faces of one of said glue applying rolls being out of alinement with the said faces of the other of said glue applying rolls, whereby said glue applying rolls will apply 50 stripes of glue to the blank moving in one direction past said rolls, the totality of said stripes forming a continuous zone of glue on the blank, the weight exerted through said glue applying rolls to said supporting roll 55 being the sole means of applying pressure therebetween, a gear wheel carried by said supporting roll, and gear wheels carried by said glue applying rolls, meshing with said first gear wheel and driven thereby to drive 60 said glue applying rolls.

10. In a gluing machine for applying glue to blanks, in combination, a receptacle for the glue, glue applying rolls, a feed roll adapted to dip in the bath of glue in the receptacle, a gear wheel rigid with said feed roll for rotating the same, a driving gear wheel rotating about a fixed axis and adapted to drive said first named gear wheel when meshing therewith, arms supporting said feed roll and adapted to swing said feed roll out of contact with the glue and away from said driving gear to disengage said driven gear therefrom, and means for adjusting the axis of rotation of said arms away from said driving gear wheel before swinging said arms to remove the feed roll from the bath. 100 105 110

60 said glue applying rolls.
8. In a gluing machine for applying glue to a blank, in combination, a receptacle for the glue, a pair of glue applying rolls mounted opposite to each other and each 65 having spaced glue applying faces for ap-

11. In a gluing machine for applying glue to blanks, in combination, a frame, a supporting roll rotatably mounted in said frame, glue applying rolls supported on said supporting roll for applying glue to the blank, a driving gear wheel rigid with said supporting roll, a receptacle for the glue, a feed roll arranged to dip in the glue in said receptacle for carrying the glue to said supporting roll, a driven gear wheel rigid with said feed roll and meshing with said driving gear wheel, a pair of arms for supporting said feed roll having pivotal supports on said frame, and means for adjusting said pivotal supports away from said driving gear wheel to disengage said driven gear wheel therefrom, said arms being adapted to 120 125 130

swing up and carry said feed roll out of contact with the glue.

12. In a gluing machine for gluing blanks, in combination, a frame, a supporting roll mounted rotatably therein, said frame having guides disposed on opposite sides of the axis of said roll, a pair of glue applying rolls having shafts received respectively in said guides and having glue applying faces 10 rolling on the surface of said supporting roll on their under sides and adapted to apply the glue to the passing blank on their upper sides, a driving gear wheel rigid with said supporting roll, gear wheels carried by said shafts and meshing with said driving gear wheel to drive said glue applying rolls, a receptacle for the glue below said supporting roll, a feed roll over said receptacle adapted to dip in the bath of glue therein for carrying the glue to said supporting roll, a driven gear wheel rigid therewith and meshing with said driving gear wheel to drive said feed roll, a pair of arms supporting said feed roll and having pivotal supports on said frame enabling said arms to swing up to withdraw the said feed roll from the bath, and means for adjusting the arms on said pivotal supports to disengage the driven gear carried thereby from said driving gear.

13. In a gluing machine, in combination, a glue applying roll having separated glue applying faces, a roll supporting said glue applying roll and receiving pressure from

said glue applying faces, means for rotating 35 said second named roll, and means for shifting said second named roll longitudinally to and fro to shift thereupon the points of contact with said glue applying faces.

14. In a gluing machine, in combination, 40 a glue applying roll having a plurality of separated glue applying faces, a roll in contact therewith for carrying glue to said glue applying faces, and means for shifting said second named roll longitudinally to and fro 45 while rotating.

15. In a gluing machine, in combination, 50 a pair of glue applying rolls each having separated glue applying faces, a supporting roll for supporting the same having a yielding covering for contacting with said glue applying faces receiving pressure therefrom and for transferring glue thereto, a glue feeding roll in contact with said supporting roll, means for feeding glue to said feeding 55 roll, and means for longitudinally shifting said supporting roll to and fro to distribute the glue received from said feed roll and to shift the points of support of said glue applying faces on said yielding covering. 60

In testimony whereof I have hereunto set my hand in presence of two subscribing witnesses.

HARRY B. SMITH.
